[57] CLAIM

The ornamental design for a combined personal alarm and LCD clock, as shown and described.

DESCRIPTION

FIG. 1 is a perspective view, as seen from the right, of a combined personal alarm and LCD clock, showing my new design, with the broken line showing for illustrative purposes only and forming no part of the claimed design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof;

FIG. 8 is a perspective exploded view similar to FIG. 1 but with the clock portion removed; and,

FIG. 9 is a rear elevational view of the clock portion of the present design.
